[57] CLAIM

The ornamental design for a combined holder and press for tea-bags, as shown and described.

DESCRIPTION

FIG. 1 is a right side elevational view of a combined holder and press for tea-bags showing my new design, with the left side elevational view being a mirror image;

FIG. 2 is a front elevational view;

FIG. 3 is a rear elevational view;

FIG. 4 is a top plan view, with the bottom plan view identical;

FIG. 5 is a top perspective view in a partially open position;
FIG. 6 is a top perspective view in a completely open position;

FIG. 7 is a bottom perspective view in a completely open position; and,

FIG. 8 is a bottom perspective view in a completely open position with the tea bag and cup shown in broken lines for illustrative purposes only and forming no part of the claimed design.
